GUIDE SHELL

William J. Delp, Greenville, Mich., assignor to
 Gibson Refrigerator Company, Greenville,
 Mich., a corporation of Michigan

Application September 15, 1948, Serial No. 49,390

3 Claims. (Cl. 219—37)

1

This invention relates to a guide shell and to methods of forming the same. The invention is particularly useful in the forming of a guide shell for an adjustable deep well burner or cooker. The methods are advantageously employed in the forming of walls, guides, and seats in a deep well cooker in which the burner is moved vertically within the guides. It will be understood that the invention is applicable to other uses.

An object of the invention is to provide for the forming of a guide shell or cylinder in which guides and seats are formed within the shell by few operations, while at the same time providing an accurate and sturdy structure, the guides being effective for reinforcing the cylinder in vertical and horizontal planes. A further object is to provide a rapid method for the forming of a guide shell or cylinder through the use of a few sequential steps and while providing a sturdy reinforced structure. Yet another object is to provide a new guide shell structure and a new method for forming the same in which a blank of metal or other suitable material is converted by a modicum of operations into an accurate shell structure providing spaced channels reinforcing the shell material both vertically and laterally. Other specific objects and advantages will appear as the specification proceeds.

The invention is illustrated, in several embodiments by the accompanying drawings, in which—

Figure 1 is a top plan view of a deep well cooker embodying my invention; Fig. 2, a side view in elevation; Fig. 3, a plan view of a rectangular strip from which the shell of the cooker is formed, the strip being shown with segments struck therefrom; Fig. 4, a top plan view of the shell formed by securing the edges of the strip shown in Fig. 3 in overlapping relation; Fig. 5, a broken perspective view of an outer wall portion of the shell structure shown in Fig. 4; Fig. 6, a broken plan view of a portion of the blank from which a modified form of cylinder embodying my invention is formed; Fig. 7, a view similar to Fig. 6 but showing a second step in the process; Fig. 8, a detail sectional view, the section being taken as indicated at line 8—8 of Fig. 7; Fig. 9, a broken detail sectional view, the section being taken as indicated at line 9—9 of Fig. 7; Fig. 10, a broken perspective view of the exterior portion of the cylinder shown in Figs. 6 to 10 inclusive; Fig. 11, a plan view of a blank illustrating the first step in another method embodying my invention; Fig. 12, a view similar to Fig. 11 but showing a second step in the method; and Fig. 13, a broken perspective view showing the structure produced

2

by the method illustrated in Figs. 11 to 13 inclusive.

In the illustration given in Figs. 1 to 5 inclusive, 10 designates a cylinder having three U-shaped channels 11 formed therein, the edges of the cylinder being united by spot welding, seam welding, riveted joints, at 12, as shown more clearly in Fig. 4. Secured to the top edge portion of the cylinder 10 is a top ring member 13 having a suspension flange 14 adapted to rest upon the top plate of a cooking range, etc. The lower end of the cylinder or shell 10 is enclosed by a ring 15. A heating element of well-known construction is mounted within the cylinder 10 for movement in a vertical plane. The heater consists of a frame 16 upon which is mounted an electric resistance coil 17. The frame is equipped with laterally-extending guide studs 18 received within the guide channels 11. Since the heating unit 20 is well known, a further detailed description is believed unnecessary.

I have discovered that the shell of the deep well cooker or of any guide cylinder of the character illustrated can be formed in an accurate 25 fashion and with a minimum of steps by employing the following method. Starting with a rectangular blank, as illustrated in Fig. 3, I cut away from the blank in an initial step the segments illustrated in the figure. The segments are 30 cut away at three points so as to provide for three guide channels. It will be understood, however, that any desired number of channels may be formed by the method described. In the cutting operation, a recess 19 is formed at the upper 35 edge portion of the cylinder blank, and below the recess 19 is formed an arcuate recess 20. The arcuate recess 20 preferably provides a depression or seat 21, as illustrated more clearly in Figs. 2 and 3. A recess 22 is also formed in the 40 cutting step at the bottom edge of the strip. By using a single die, all of the recesses illustrated can be readily formed in a single operation.

Also, as a part of the cutting step, location openings 23 may be pierced to aid in the accurate 45 drawing of the metal in the second step.

In the second operation or step, the metal between the recesses 20 and 22 is pressed outwardly to form the U-shaped channel 11, as illustrated more clearly in Figs. 4 and 5. In the 50 drawing or pressing operation, a portion of the metal employed to form the U-shaped strip is indicated by the numeral 24, and portions on each side thereof form the side walls 25 of the U-shaped channel. The forming of the side walls 25 from the initial wide strip of metal be-

tween the recesses 20 and 22 results in contracting this portion of metal and at the same time bringing together the edges of the metal about each recess 19, as shown more clearly in Fig. 5.

By providing the spaces 19, 20 and 22, the pressing of the metal to form the U-shaped channels does not bring about a thinning or attenuating of the metal. Instead, the spaces or recesses described permit a simple pressing outwardly of the metal without weakening the metal while, at the same time, narrowing the recesses and preferably bringing the edges of the metal about the recess 19 together.

In the next step, the rectangular strip illustrated in Fig. 3, having the U-shaped channel formed therein, is rolled into the form of a cylinder and the overlapping edges united by welding at 12, as illustrated in Fig. 4. It will be understood that the edges may be butt-welded or secured together by any other suitable means. The blank may be formed into a cylinder by simply connecting the ends or by first forming the blank upon a die or other suitable means.

In the final assembly operation, the upper ring 13 is attached to the cylinder 10, and the lower ring 15 is secured to the lower end of the cylinder. In the specific illustration given, the U-shaped channel 11 terminates short of the bottom of the cylinder and the ring 15 extends across the recess 22 and provides a stop below the U-shaped channel adapted to support one of the studs 18 of the burner or heater unit. In the resulting structure, the studs 18 of the burner unit are guided by the U-shaped channels 11 in a vertical path and then, upon leaving the U-shaped channels 11, are guided by the arcuate recess 20 toward the upper seats 21 for the studs.

In the modified method illustrated by Figures 6 to 10 inclusive, the operation is the same as above described except that a portion of the metal about the recess 20 is pressed inwardly to form flanges 26 upon which the studs 18 are guided. If desired, the flanges 26 may be formed by pressing the metal outwardly in the second step in which the channels 11 are formed by the pressing outwardly of vertical strips of the metal. The cylinder 10^a, after the drawing of the flanges 26, is formed in the same manner as already described in which the strip is rolled or pressed into the form of a cylinder and the edge portions of the cylinder united.

In the illustration given in Figs. 11 to 13 inclusive, a cylinder 10^b is formed by the sequence of steps illustrated in Figs. 11 and 12. In the first step, the recess 27 is formed, and below the recess a circular portion of the metal is cut away, providing the circular recess 28. In the second step, the metal is pressed outwardly to form a U-shaped channel 11^b and, in this operation, not only is the vertical portion of the channel pressed outwardly but in the same operation the arcuate portion 27 is pressed outwardly, as shown more clearly in Figs. 12 and 13. In the pressing of the portion 27 outwardly, the opening 28 is caused to assume an oblong or elongated shape. The edges of the blank are united to form the cylinder, as heretofore described. By providing the aperture 28, I find that the channel 11^b can be drawn together with the arcuate portion 27 thereof without substantially wrinkling or distorting the metal.

In all of the methods illustrated, the provision of the recess at the upper edge and/or lower edge of the blank formed of metal or other suitable material, permits the drawing of

the channels with arcuate upper portions providing seats, without attenuating or weakening the metal. The outward pressing of the metal to form the channels simply takes up

the space provided by the recesses 19 and at least a part of the space provided by the recesses 22 so that the edges of the metal approach each other. The subsequent addition of the upper ring 13 and the uniting of this to the upper portion of the cylinder 10 strengthens the slotted portion of the metal above the seat recess 21 and provides an extremely sturdy structure. The operations described for forming the blank into the completed cylinder are few and can be carried through expeditiously. The blank shown in Fig. 1 or a long ribbon of metal from which the rectangular blanks are subsequently cut, may, in one single cutting operation, have the recesses described formed therein. In the second step, the metal is pressed outwardly to form the U-shaped channel (one at a time) and, if desired, flanges about the arcuate portion of each guide channel. The blank may then be readily bent or rolled into cylindrical form and united as described. The resulting shell or cylinder is strengthened by the vertical U-shaped channels and by the flanges about the arcuate portions of the guide slots so that the blank is stiffened not only vertically by the channels but also in a horizontal plane by the laterally-extending flanges about the arcuate slots.

It is contemplated that the structure herein described may be formed not only of steel but also of aluminum and other suitable metals.

While in the foregoing specification, I have set forth specific structures in considerable detail for the purpose of illustrating embodiments of my invention, it will be understood that such details of structure and method may be varied widely by those skilled in the art without departing from the spirit of my invention.

I claim:

1. A guide shell for a deep well cooker and the like, comprising a strip in the form of a cylinder with the edge portions of the strip secured together, said cylinder having a vertical U-shaped channel having three sides joined together substantially at right-angles and a laterally-extending channel communicating with the top of the vertical channel, said cylinder being divided at a point between said laterally-extending channel and the top of the cylinder.

2. A guide shell for a deep well cooker and the like, comprising a strip in the shape of a cylinder with the edges of the strip secured together, said shell having a plurality of spaced U-shaped channels extending vertically therein, each of said channels having three sides joined together substantially at right-angles and laterally-extending openings in said shell communicating with the top of said vertical channels, said shell having a slit therein between said vertically-extending channel and the top of the shell.

3. A deep well cooker comprising a shell having outwardly-extending U-shaped channels extending vertically therein and having also recesses communicating with said vertical channels and providing seat depressions, said shell being divided at points between said recesses and the adjacent outer edge of the shell, an upper suspension ring enclosing the upper divided edge portions of said shell and secured to said shell portion, and a lower ring enclosing the lower portion 70 of said shell, said lower portion of the shell being

recessed at a point below each of said U-shaped channels and said lower ring enclosing the lower edge portion of the shell providing a stop below each U-shaped channel.
